(57) **CLAIM**

The ornamental design for landscape edging blocks, as shown and described.

DESCRIPTION

FIG. 1 is a top view of a first landscape edging block and a second landscape edging block, both according to the present invention, and, illustrated in a first position; where no claim is made to the rough, upper surface;

FIG. 2 is a bottom view of the first and second landscape edging blocks according to the present invention, and, illustrated in the first position;

FIG. 3 is a back side view of the two landscape edging blocks according to the present invention in the first position; where no claim is made to the rough, upper surface;

FIG. 4 is a front side view of the two landscape edging blocks according to the present invention in the first position; where no claim is made to the rough, upper surface;

FIG. 5 is a right side view of the two landscape edging blocks according to the present invention in the first position; where no claim is made to the rough, upper surface;

FIG. 6 is a left side view of the two landscape edging blocks according to the present invention in the first position; where no claim is made to the rough, upper surface.

The broken line showing of portions of the brick is for illustrative purposes only and forms no part of the claimed design.
